SIGNAL CONTROL

Le Roy C. Paslay, Dallas, Tex., assignor to National Geophysical Company, Dallas, Tex., a corporation of Delaware

Application May 9, 1939, Serial No. 272,563

7 Claims. (Cl. 179—171)

This invention relates to alternating current transmission systems, and more especially to the control of current in such systems wherein thermionic tubes are employed, as, for example, in signalling systems.

The invention is especially advantageous in connection with amplifier systems designed for use in geophysical exploration work, and comprises an improvement on the invention described in my application for U. S. Letters Patent Serial Number 159,994, filed August 19, 1937.

The control of alternating current transmission, especially of signals whether of low frequency or high frequency, has been the subject of considerable investigation by those skilled in the art. Such investigations have included both manual and automatic controls, the latter usually having been referred to as automatic gain controls or automatic volume controls. Practically all successful automatic gain control systems have been based on the principle of amplifying the signal in a grid-controlled thermionic tube, rectifying part of the amplified signal and applying the rectified signal, as a biasing potential, to the control grid of the signal amplifier. A large number of modifications and variations of that fundamental system have been devised. However, it has been recognized that the control of gain in that manner inevitably produces a certain amount of distortion and other attendant disadvantages of a nature depending upon the circumstances. In certain control systems prior to the present invention some of these disadvantages resulted from the reaction of the control current upon the current being controlled when the apparatus involved became unbalanced, and in other systems a disadvantage resulted from the fact that if the gain control potential were to be applied to a reasonably small number of amplifier tubes the range of control could not be large without introducing distortion of a nature depending upon the amplification characteristics of the thermionic tubes employed. These and many other disadvantages in the prior gain control systems are overcome by the system of the present invention.

The control, and especially the automatic control, of gain is difficult in respect to low frequencies. This is particularly true in the event that the low frequencies comprise unmodulated signals. For instance, in geophysical exploration work comprising the seismometric recording of earth vibrations resulting from the detonation of an explosive, the frequencies involved may cover a range of between about 30 and 200 cycles

per second while the amplitude of the vibrations may vary as much as 20,000 to 1 in 5 seconds, or so. Graphical records of such variations are difficult or impossible to make and to read when 5 the amplitude of the vibrations has decreased to a low value, although frequently these very vibrations have important significance to a geophysicist. Consequently it is important, first, that the signals be amplified more as they become weaker and, second, that a minimum of 10 distortion be introduced in doing so. The present invention meets these requirements with considerable success, these and other of its valuable features being applicable both to manual 15 and automatic gain control systems. For a more detailed discussion of geophysical work and apparatus, and the manner in which automatic gain control would be employed therein, reference is made to my mentioned patent application.

The preferred form of the present invention 20 contemplates the automatic control of alternating current or signals in such manner that the control system itself introduces no appreciable 25 effect in the signal transmission channel except the desired control of transmission or gain. In accordance with the invention, the alternating current or signal is controlled by a gain control or an attenuating element responsive to another 30 or control current having characteristics separably different from those of the current or signal being controlled.

A better understanding of the invention will 35 be had from a consideration of the following specification, and from the drawings in which:

Fig. 1 is a block diagram of an embodiment of this invention wherein the principal elements are labeled;

Fig. 2 is a circuit diagram of a system more 40 generally represented in Fig. 1; and

Fig. 3 is an equivalent diagram of the gain 45 control element represented in Figs. 1 and 2.

Referring first to Fig. 1, there are shown eight 50 blocks, those numbered 1, 2, 3 and 8 representing elements in an alternating-current transmission or signal channel, and those numbered 4, 5, 6 and 7 representing elements in a control channel.

In the embodiment shown herein by way of a 55 preferred example, it is assumed that the signal or other alternating current is to be automatically controlled. Accordingly, the signal is first amplified in amplifier 1, and is then passed through the gain control element 2 where the current to be controlled (hereinafter for con-

venience referred to as "the signal" is attenuated in the desired manner. This gain control element preferably is of a type having the characteristic that its control effect varies with variation of current through it. The controlled signal then passes through a second amplifier 3 and thence into an appropriate utilization device 8, which, in the assumed case of geophysical exploration apparatus, would usually be a graphical recording device.

Still referring to Fig. 1, the output of the second amplifier 3 is also coupled to a rectifier 4, the rectified current from which actuates a direct-current amplifier 5. Also included in the control channel is a local oscillator 7 which supplies alternating current to the input of an amplifier 6 at a frequency of an order of magnitude different from that of the signals, this frequency preferably being considerably higher than that of the signals. For reasons later to be explained in connection with Fig. 2, control-current amplifier 6 is arranged not only to amplify the output of the oscillator, but also to double the frequency thereof. The output circuit of amplifier 6 is connected so that the output current therefrom flows through gain control element 2, thus controlling the attenuation effect introduced by that element in the signal channel. Direct-current amplifier 5 is so coupled to control-current amplifier 6 that the output current of amplifier 6 is caused to vary in accordance with the variation of the direct potential developed in the output circuit of amplifier 5. Thus the gain control effected by element 2 may be said to be a function of the variation of the output of rectifier 4.

The circuit diagram of a system which follows the general arrangement of Fig. 1 is shown in Fig. 2 wherein sections of the components are enclosed in dotted lines forming blocks identified by reference characters which correspond to those of Fig. 1. Accordingly, a first amplifier 1 is shown coupled to the source of signals by an input coupling transformer 18 designed to accommodate the frequency range of the signals (here assumed to be approximately 30 to 200 cycles). The amplifier comprises two stages of the resistance-coupled type. Thermionic amplifying tubes 9 and 10 are here shown for simplicity as being separate triodes, although in practice they might comprise a duplex triode, such as the type 6C8. Biasing resistors R1 and R4 together with their by-pass condensers C1 and C3, respectively, are of the values and types usually employed with tubes of this character. Suitable values for the anode and grid resistors R2 and R3, respectively, and coupling condenser C2 are given in a table set forth hereinafter, as are the electrical values of other of the components.

Gain control element 2 is coupled to the output of amplifier 1 through resistor 5 and condenser C4. This gain control, or attenuating, element may include a pair of resistance or attenuating elements 11, 12 having non-linear characteristics. The effective resistance of such a non-linear element varies in accordance with the current flowing therethrough, and in this instance the effective resistance decreases with increase of current therethrough, although such relation is not usually a direct proportion. In order to effect the desired control of attenuation the elements shown are connected in shunt to the signal channel so that the attenuation is

increased as the effective resistance decreases.

Before describing the components of this portion (2) of the system in detail, reference is made to Fig. 3 which represents in simplified form the equivalent of the components represented between terminals a, b, and c, d of Fig. 1. Resistance elements having non-linear characteristics are represented in Fig. 3 by variable resistors 11, 12. From this it can readily be seen that signals transmitted through the channel between a, b and c, d will be attenuated in accordance with the effective resistance of the attenuating elements 11 and 12 connected in shunt in the signal channel. When the attenuating elements have a lower effective resistance than the series resistors R6 and R7 the attenuation will be much greater than when the attenuating elements have a higher effective resistance than the resistors R6 and R7. The present invention provides means for controlling the effective resistances of the attenuating elements without undesirably affecting or otherwise changing the characteristics of the signals.

Referring again to Fig. 2, the variable resistance elements 11 and 12 may comprise double-diode thermionic tubes such, for example, as the type 7A6, although any suitable non-linear impedance elements, capacitive, inductive or resistive, may be substituted. For example, if rectifiers of the copper oxide type be substituted they would also be connected as shown in Fig. 2, so that the alternating current will flow through the device in both directions. On the other hand, if a resistor of a non-linear type such as that known as "Thyrite" be employed, only two such resistor elements need be employed, i. e., one to replace tube 11 and the other to replace tube 12. The non-linear resistance characteristics of a diode are well-known and are described, for example, in Morecroft's "Electron Tubes," 1933, pp. 72-73. Other rectifiers, such as the copper oxide rectifier, are known to have similar characteristics.

The effective resistance of elements 11 and 12 is, in accordance with this invention, varied and controlled by passing through such elements a current having characteristics sufficiently different from those of the signals to make practicable effectively complete separation of the two currents, thus avoiding any distortion or other undesirable effect on the signals by the control current. To this end, an alternating control current of, say, 400,000 cycles is supplied through leads 32 to a circuit comprising inductances 19 and 21 and variable condenser 31 which is tunable to 400,000 cycles. Inductances 19 and 21 comprise the primaries of transformers of which the secondaries are 20 and 22, respectively. Consequently, the alternating control current at that frequency is thus caused to flow in secondaries 20 and 22, respectively, and hence in common through the circuit 20, C5 and 11 and the circuit 22, C1, and 12. Condensers C5 and C1 are of values offering very high impedance to the signal frequency but low impedance to the control-current frequency. The inductance of secondaries 20 and 22 is so small as to offer essentially no impedance at the signal frequency. Battery 28 which may be a part of battery 27 and may, therefore, be tapped from a suitable voltage divider of a direct-current power supply system, provides a biasing potential to each of tubes 11 and 12 in order to bias those tubes just to the point of essentially infinite resistance. By-pass condenser C6 and resistors R16 and R17 com-

plete this biasing system. An equivalent bias could be obtained by omitting components 28, R16, R17 and C6 and substituting separate biasing batteries correctly connected as to polarity between either the anode or the cathode of each of the double diodes and the common return lead shown as connecting terminals *b* and *d*. After the correct adjustment of such a biasing potential is made, if any current whatever flows through the diodes the internal resistance thereof is effectively decreased. Such a decrease is, of course, effective in regard to the signal current, which being of so low a value across the nonlinear element does not cause a sufficient change in resistance to produce distortion of the signal.

After the signal passes through the gain control element 2, it is amplified in the second amplifier 3 which may be substantially identical with the first amplifier 1. The output circuit of the second amplifier includes primary winding 24 of an output transformer 23 which should be designed for the frequency range of the desired signals. This transformer may include two secondary windings, namely, secondary 25 which may be connected to a signal utilization device 8, and another secondary 26 which may be connected to a rectifier 4. In this instance a full-wave rectifying device 15 is employed, and hence secondary 26 includes a center tap connection. Any suitable full-wave or half-wave rectifier may be used for this purpose. Thus, a predetermined part of the signal energy appearing in transformer 23 is caused to flow through rectifier 4 and be rectified into direct or pulsating unidirectional current. Any undesired pulsations in the direct-current output of rectifier 4 may be filtered out, if desired, by the use of filter elements well known in the art.

The output of rectifier 4 is, in this instance, connected to the input of a direct-current amplifier 5 comprising a thermionic tube 16 and associated elements. These elements include voltage divider resistors R13 and R14, the terminals of which are connected across the anode-potential battery or voltage source 27 which supplies the anode potentials for all of the thermionic tubes. Reactor 30 and condenser C12 together comprise a filter which will remove alternating current components from the amplified direct current, the inductance of reactor 30 and the capacitance of condenser C12 being both high. The rate at which condenser C12 charges is determined largely by the anode resistance of tube 16 plus the resistance of R13; while the discharge rate of C12 depends largely on the load drawn by the thermionic tube 17, i. e., on the effective resistance of the anode circuit of tube 17. In the particular system herein illustrated the constants controlling the rate of charge and discharge of condenser C12 have been chosen to cause rapid depression to strong signals and slow recovery to weak signals. In selecting the value of condenser C12 the fact should also be borne in mind that this condenser determines in part the rate which the automatic gain control action incurs upon each change in the magnitude of the signal. The battery 29, or other appropriate source of potential, furnishes a bias beyond cut-off for tube 16 so that an initial potential of about 1.5 volts output from rectifier 4 is required before tube 16 starts to function. This furnishes the required "delay" in order that the system produce the comparatively flat automatic gain control characteristic which is desirable in this particular embodiment.

In the event that a manual control be desired, instead of the automatic control herein illustrated, it is necessary only to substitute for elements 4 and 5 an equivalent source of manually controlled direct-current potential across the condenser C12.

A local oscillator represented by block 7 comprises any convenient source of alternating current and hence has not been shown in detail. 10 Such independent source of alternating current, which in this case may be assumed to have a frequency of 200,000 cycles, is coupled by means of condenser C13 and resistor R15 to control-current amplifier 6. This control-current amplifier includes thermionic tube 17, which for convenience may comprise one section of a duplex triode tube such as type 6C8. The other section of such tube may comprise tube 16 which for simplicity has been drawn as a separate tube.

15 It will be noted that the output circuit of amplifier tube 17 includes the tuned circuit 19, 21, 31 and condenser C12. The only source of anode potential for tube 17 is the direct-current potential appearing across condenser C12, but this condenser being of high capacitance offers negligible impedance to alternating current of the frequency appearing in the mentioned output circuit. This direct-current potential even when it fluctuates in accordance with the output of rectifier 4, never reaches a high value, so that actually, the anode potential supplied to tube 17 is always greatly lower than would be specified for normal operation of a tube of the type employed in this control-current amplifier. For this reason a comparatively small change in value of direct-current potential across condenser C12 will effect a rather large change in the magnitude of control current supplied to the coupling circuit which includes condenser 31.

20 40 By reason of the circuit constants, grid bias and anode potential employed in connection with tube 17, a rather large current component at double the input frequency appears in the output circuit of tube 17. Thus, in practice, the tuned circuit 19, 21, 31, may be adjusted to 400,000 cycles, which in this instance will be a much higher frequency than the signals. Consequently, because of the values of the circuit components this comparatively high frequency of 400,000 cycles will normally be confined to the gain-control element 2. Sometimes, however, it may be desirable to connect in each or either of amplifiers 1 and 3 a band-pass filter tuned to pass only the signal frequency or the range of signal frequencies.

25 45 50 55 60 65 70 75 With the system above described it is possible to achieve a very complete control of the high-frequency control current without neutralizing the grid-anode capacitance of tube 17, for the following reasons: As shown, the resonant circuit 19, 21, 31 is tuned to approximately 400,000 cycles, so that substantially no potential at 200,000 cycles is developed in the output circuit of tube 17, whereas a potential at 400,000 cycles is developed in that circuit. This 400,000 cycle current, being the result of the frequency-doubling function of tube 17, exists in the anode circuit only by reason of the tube's thermionic action and therefore is subject to control by variation of the anode potential independent of any interelectrode capacity coupling. Under different circumstances equivalent results may be had by substituting a neutralized triode or a pentode having a shielded grid, and employing such a tube as a straight amplifier and not as a dou-

bler as well. In that event the oscillator should be adjusted to supply control current at the same frequency as that to which the coupling circuit 19, 21, 31 is to be tuned. If, on the other hand, the oscillator frequency be dictated by other considerations, that frequency might be set as required, and the control-current amplifier operated as a frequency doubler even though it be neutralized or comprise a shielded grid pentode. When the capacity coupling effect is minimized the direct-current control potential may be impressed on the control grid instead of in the anode circuit, although this is usually not to be preferred.

To complete the foregoing description of the specific apparatus represented in Fig. 2, but without implying any limitation as to the scope of the invention, the following electrical values of circuit elements are suggested:

R ₂ —250,000 ohms	C ₂ —.05 μ f.
R ₃ —1 megohm	C ₄ —.05 μ f.
R ₅ —250,000 ohms	C ₅ —.001 μ f.
R ₆ —.5 megohm	C ₆ —40 μ f.
R ₇ —.5 megohm	C ₇ —.001 μ f.
R ₉ —250,000 ohms	C ₁₁ —.1 μ f.
R ₁₀ —1 megohm	C ₁₂ —12 μ f.
R ₁₂ —75,000 ohms	C ₁₃ —.01 μ f.
R ₁₃ —.5 megohm	27—300 volts
R ₁₄ —.1 megohm	28—6 volts
R ₁₅ —100,000 ohms	29—2 volts
R ₁₆ —4,000 ohms	30—320 henries
R ₁₇ —2,000 ohms	

The operation of the transmission system above described is, briefly, as follows: With the oscillator 7 generating a frequency of say 200,000 cycles, a signal preferably of fixed amplitude is impressed on input transformer 18. Variable condenser 31 is then adjusted slowly until the amplitude of the signal appearing at the output 8 of the transmission channel is at a minimum. This will usually occur when the adjustment of condenser 31 has tuned the coupling circuit 19, 21, 31 to a frequency slightly different from that of the current appearing in the leads 32. The apparatus is then ready for use. Assuming that the circuit components are of the values above stated and that no signal is present in the signal channel, an impressed signal, in the first instant, will be amplified in amplifier 1 and will pass through the gain control element 2 without appreciable attenuation because the resistance of the attenuating elements 11 and 12 will then be very high. The signal will next be further amplified by amplifier 3 and will then pass out through secondary 25 of output transformer 23 to operate a recorder or other device responsive to the signals. Part of the amplified signal will be rectified by rectifier 4 and will be amplified by the direct-current amplifier 5. In the system illustrated the potential supplied to the anode circuit of tube 17 will be sufficient to allow control current to flow in the leads 32 when the rectifier output reaches about 1.5 volts. As the voltage in the output circuit of rectifier 4 increases, the control current in the leads 32 increases until it reaches a maximum, thus resulting in maximum signal attenuation when the output voltage from the rectifier reaches about 1.9 volts. Such a variation of about 0.4 volt from the rectifier represents a variation in signal strength of roughly 20,000 to 1, which means that a signal-strength variation of that order of magnitude may be automatically controlled with substantially no signal distortion. Conversely, as

the signal strength decreases, the output potential of the rectifier drops, the control current through the attenuators 11 and 12 decreases and the effective attenuating resistance increases, thus decreasing the attenuation of the signals in proportion.

I claim:

1. In a signalling system, a signal channel including a first signal amplifier, a signal gain control element, a second signal amplifier and a signal utilization device coupled in the order named; and a control channel including an oscillator generating current at a frequency of an order of magnitude different from that of the signals, a third amplifier coupled to said oscillator and adapted to double the frequency of the current from said oscillator, a rectifier and a direct-current amplifier; the output of said second amplifier being coupled to said rectifier and the output of said rectifier being coupled to said direct-current amplifier, connections between said direct-current amplifier and said third amplifier and connections between the output of said third amplifier and said gain control element.

2. In a signalling system, a signal attenuator having the characteristic that its attenuating effect increases with increase of current through it, a signal-frequency amplifier coupled to the output of said attenuator, a rectifier coupled to the output of said signal-frequency amplifier, a source of control current at a frequency considerably higher than the frequency of the signals, a control-current amplifier for amplifying said control current, the output of the control-current amplifier being coupled to said signal attenuator, a direct-current amplifier connected to the output of said rectifier, and connections from the output of said direct-current amplifier to the anode circuit of said control-current amplifier, the direct-current potential supplied by said direct-current amplifier being the dominant source of anode potential for said control-current amplifier.

3. In a signalling system, a signal channel adapted to transmit signals at frequencies between approximately 30 and 200 cycles per second, said signal channel including a first signal amplifier, a signal gain-control element having the characteristic that its effective resistance decreases with increase of current through it, a second signal amplifier and a signal utilization device coupled together in the order named; a control channel including an oscillator generating current at approximately 200,000 cycles per second, a third amplifier connected to amplify current from said oscillator and arranged to double the frequency thereof, a rectifier coupled to the output of said second amplifier, the output of said rectifier being connected to a direct current amplifier, connections between said direct current amplifier and said third amplifier, and connections between the output of said third amplifier and said gain control element, whereby the gain is effectively regulated automatically in accordance with the amplitude of the signals.

4. In a signalling system, a signal channel adapted to pass only low frequencies, a signal attenuator comprising an attenuating element connected effectively in said channel, said element having the characteristic that the effective attenuation thereby varies with change of current therethrough, a source of control current at a frequency of an order of magnitude one

thousand times that of the signals, control means including a frequency doubler coupling current from said source to said element, and a variable source of direct current connected to control the output of said frequency doubler.

5. In a signalling system, a low-frequency signal channel, a signal attenuator comprising a pair of resistance elements connected effectively in shunt with said channel, said elements having the characteristic that the effective resistance thereof decreases with increase of current therethrough, a source of current at a fixed frequency considerably higher than that of the signals, coupling means tuned substantially to said fixed frequency connected to couple said source and said elements in common whereby current at said higher frequency is caused to flow through said elements and current at said low frequency is prevented from flowing through said elements, and control means for adjusting the magnitude of said current including a vacuum tube the grid circuit of which is connected to said source and the anode circuit of which includes said coupling means and an adjustable source of direct-current potential.

6. In a signalling system, a signal channel, a signal attenuator comprising an attenuating element connected effectively in said channel, said element having the characteristic that the effective attenuation thereby varies with change of current therethrough, a source of control current at a frequency of an order of magnitude greatly higher than that of the signals, a thermionic amplifier the input of which is connected to the source of control current and the output of which is coupled to said attenuating element, a rectifier coupled to said signal channel, the

output of said rectifier effectively providing the entire source of direct-current anode potential connected to the anode of said thermionic amplifier, said direct current anode potential being 5 greatly lower than the potential specified for normal operation of said amplifier, and means for varying said anode potential and thus the attenuation of the signals.

7. In a low-frequency alternating-current transmission system, an attenuating element effective to control the transmission characteristics of said system, said element comprising a device of which the effective resistance varies according to the current therethrough, a source 10 of alternating current connected to said device of constant frequency and variable in magnitude, the frequency of the current of said source being greatly higher than the highest frequency of the current in said transmission system, a vacuum tube a grid of which is coupled to said source of high-frequency current and the anode of which is coupled to said device so as to cause a high-frequency current to flow therethrough, and a rectifier coupled directly to the output of said 15 transmission system and connected to effectively supply the entire anode potential for said vacuum tube by rectification of said low-frequency current, so as to automatically vary the magnitude of said high-frequency current in accordance with the magnitude of the low-frequency current at the output of said transmission system, and means for separating the currents of 20 said two different frequencies whereby to prevent distortion of the low-frequency current in 25 said transmission system.

LE ROY C. PASLAY.
